OF WORCESTER, MASSACHUSETTS, A CORPORATION OF MASSACHUSETTS

GRINDING MACHINE

Application filed October 1, 1928. Serial No. 309,521.

This invention relates to machines for precision grinding. Its object is to provide a machine for automatically grinding work pieces to size uniformly within the closest 5 possible limits.

In the art to which this invention relates, grinding machines are employed which include feeding mechanism for relatively moving the work and the grinding element, and 10 caliper mechanism acting to caliper the diameter of the work during the grinding operation and to control automatically the action of the feeding mechanism. In the organization of such machines, the work 15 supporting and grinding elements are necessarily of rigid and heavy construction and considerable power is required for operating the feeding mechanism to effect rapid and positive infeeding and separating movements of the work and the grinding element, a condition which militates against 20 extreme delicacy of control. On the other hand, to insure the accurate operation of the caliper mechanism this must be extremely light in its construction and must 25 operate under light pressure. The area of surface of its contact points must be kept small in order to reduce the possibility of foreign matter being retained between the 30 contacts and the work and the pressure must be light to avoid marking the work, especially where it is not hardened. The conditions, therefore, under which the caliper mechanism best operates militate 35 against a powerful and positive controlling action.

With these conditions in mind, the present invention consists in caliper mechanism of novel construction wherein the caliper movement is utilized to trip a sensitive latch mechanism under conditions of light pressure and the tripping of the latch mechanism is taken advantage of in a novel 40 manner to govern an actuating system which, in turn, is utilized to control the action of the feeding mechanism. As herein shown, the actuating system comprises an electric circuit. The controlling switch of 45 this circuit is arranged to be closed manually by the operator and this operation ener-

gizes a source of power which is subsequently utilized to effect automatically a sudden and wide break of the contact members of the switch when tripped by the caliper mechanism. By using this construction, I have 55 found it possible to maintain good electrical contact under adequate pressure during the grinding operation and yet effectually to break this contact in response to an extremely slight and delicate movement of the caliper elements. 60

In this connection another feature of the invention consists in a caliper mechanism including a train of mechanism arranged to be latched under tension when contact is 65 established and having a trip acting at a point in the train remote from its point of connection with the contact member where an extremely light pressure is effective for locking the train. The caliper mechanism is arranged to act upon the trip at this point in the train and consequently a release of 70 great nicety under conditions of light pressure is provided.

Other features of the invention relate to 75 a novel feeding mechanism whereby the work and the grinding element may be moved toward and from each other accurately and positively and at speeds appropriate for the different requirements. As 80 herein shown, the grinding wheel is moved at high speed from a remote initial position into a preliminary grinding relation to the work, then fed into the work at a slow speed until a predetermined diameter is reached, 85 then held at rest while a further slight reduction of diameter takes place and finally retracted at high speed to its initial position.

To accomplish these results, the present 90 invention contemplates feeding mechanism including a plurality of clutches driven at different speeds and in different directions, together with means for timing their action and throwing them successively into operation. Certain of these clutches are controlled through the action of the caliper mechanism and others, such as that effective for producing the preliminary movement of the 95 grinding wheel, are mechanically controlled. 100

It is believed that feeding mechanism including caliper controlled and mechanically controlled driving clutches has never before been employed in machines for precision grinding.

These and other features of the invention will be best understood and appreciated from the following description of a preferred embodiment thereof, selected for purposes of illustration and shown in the accompanying drawings, in which

Fig. 1 is a view in perspective showing somewhat diagrammatically the arrangement of the grinding wheel slide and its feeding mechanism, the work and the caliper device;

Fig. 2 is a view in elevation, partly in section, of the feeding mechanism;

Fig. 3 is a plan view of the caliper mechanism;

Fig. 4 is a sectional view on the line 4—4 of Fig. 2;

Fig. 5 is a sectional view of the caliper mechanism on the line 5—5 of Fig. 3;

Fig. 6 is a sectional view of the caliper mechanism on the line 6—6 of Fig. 5;

Fig. 7 is a view partly in section of a portion of the caliper mechanism on the line 7—7 of Figs. 5 and 8;

Fig. 8 is a view in end elevation of the switch mechanism with the casing in section; and

Fig. 9 is a diagram of the electric circuit.

In the cylinder grinding machine illustrated, the grinding wheel 100 is mounted on a driven shaft 102 journaled in a cross slide 104, suitably supported by transverse ways in the machine frame, not shown. In the bottom of the grinding wheel slide is provided a half nut 106 which cooperates with a lead screw in the shaft 12 for moving the slide to carry the grinding wheel toward or from the work. The work piece to be ground is indicated by reference character 108 and is supported upon centers, one of which 110 is shown in Fig. 1 and rotated while being ground. The mechanism thus far described is well-known in commercial grinding machines such, for example, as that shown in the patent to Norton No. 762,838.

To move the grinding wheel 100 toward and from the rotating work, I prefer to employ mechanism which will now be described. The lead screw shaft 12 carries a pinion 27 which meshes with another pinion 28 on the rear end of a shaft 10, which is journaled in bearings 11, shown in Fig. 4, and all of which are carried by the machine frame. Rotation is transmitted to the lead screw shaft 12 through the shaft 10 which may be turned manually by a hand wheel 14 fast to its forward end or automatically and mechanically through a worm wheel 13 which, in turn, is driven by a worm 25 on

the left end of a lead screw driving shaft 26, best shown in Fig. 2. The worm wheel 13 may be locked to the shaft 10 or may be free to rotate upon it according as it is desired to utilize the automatic feed or the manually controlled feed. To this end, a gear 15 is rigidly secured to the worm wheel 13 and arranged to mesh with a pinion 24 formed in the rear end of a plunger 21 which is slidably mounted in a sleeve 16 to rotate therewith. This sleeve 16, in turn, is rotatably mounted in the hand wheel 14. The sleeve 16 has an integral arm carrying a locking pin 17 adapted to enter one of a series of holes 20 arranged circumferentially in a disk formed on the hand wheel 14 and being maintained in locking position by a spring, shown in Fig. 4. The plunger 21 is keyed to the sleeve 16 so that it may be retracted when it is desired to disengage the hand wheel 14 from the automatic feed mechanism.

It is desirable, for a purpose which will presently appear, to provide for changing by small amounts the angular relation of the worm wheel 13 and the shaft 10 and this may be effected by withdrawing the pin 17 and rotating the sleeve 16 by its arm to turn the plunger 21 through the desired angle and then releasing the pin to lock the sleeve and plunger in adjusted position, as determined by one or another of the holes 20.

Provision is made for rotating the driving shaft 26 at two different speeds in a direction to advance the grinding wheel toward the work and at one speed in the reverse direction. To this end, a gear 30 having a cone clutch face is loosely mounted upon the shaft 26 and arranged to be rotated at high speed in the direction of the arrow in Fig. 2, that is, forwardly at the top. This gear is driven, through an intermediate gear 113, by a gear 112 on a shaft 114 carrying a pulley 116 connected by a belt to any convenient source of power. A similar gear 32, having an oppositely disposed cone clutch surface, is also mounted upon the shaft 26 and this is arranged to be driven at a high speed in the opposite direction directly by a large gear 118 on the shaft 114. Between the clutch gears 30 and 32 is disposed a sliding clutch member 36 having oppositely disposed annular clutch surfaces adapted to cooperate with those of either gear, depending upon the direction which it is desired to drive the shaft 26. The clutch member 36 is arranged to be shifted by a forked bell crank lever 37 pivotally mounted on a stud 38 and engaging a loose ring 39 in the clutch member.

The shaft 26 also carries a gear 34, loosely mounted and arranged to be driven at slow speed in the direction of the arrow by means of a gear 120 on a shaft 122, which carries

at its outer end a set of change speed pulleys 124 adapted to be driven by a belt from any convenient source of power. A clutch member 40 is slidably keyed to a sleeve 41 upon the shaft 26 and this may be shifted to engage or disengage the clutch gear 34, so that the sleeve 41 is rotated or not. Rigidly secured to the shaft 26 is a flange 45 having a pawl 46 on its face which cooperates with a ratchet 47 formed upon a flange of the sleeve 41. The ratchet and pawl are so arranged that when the clutch member 40 is engaged with the clutch gear 34 and driven thereby the ratchet 47 will drive the shaft 26 in the same direction and at the same speed but it will at all times leave the shaft 26 free to be driven at a higher speed in the same direction by the clutch gear 32.

In order to time the rotation of the worm wheel 13 and impart to it a definite cycle of movement of more than a single revolution, the following mechanism is provided. The shaft 26 carries another worm 48 which is arranged to drive a worm wheel 49 rotatably mounted upon a stud 50. The design of the worm 48 and the worm wheel 49 is such that the worm wheel is given a slower angular movement than the worm wheel 13, making less than a revolution while the worm wheel 13 is moved through a number of revolutions sufficient to impart adequate movement to the grinding wheel slide.

The worm wheel 49 carries a cam ring 51 having inclined faces 52 and 53. A trip cam 54 is also provided upon the shaft 50 and this rotates in fixed relation with the cam ring 51. The worm wheel 49 also carries a ring 57 of insulating material having a conducting segment 58 adapted to contact with brushes 59 and 60 to close and maintain an electric circuit through them for a definite interval.

The bell crank lever 37 is swung in opposite directions to shift the clutch member 36 by the cams already mentioned and by a solenoid controlled by the caliper mechanism. For this purpose, it is provided with an arm 61 to which is pivoted a vertically disposed rod 62. The rod is encircled by a compression spring 63, tending normally to lift the arm 61 and shift the clutch member into engagement with the clutch gear 30. The rod 62 is guided in its movement by a stationary bracket 64 and is connected at its lower end to the core 65 of a solenoid 66.

The arm 67 of the bell crank lever 42 is pivotally connected to a vertical rod 68 located directly behind the rod 62, as shown in Fig. 1. This rod 68 is provided with a compression spring which tends normally to lift the arm 67 and the rod passes also through the bracket 64. Below the bracket 64 it is connected to the core 69 of a sole-

noid 70. The arm 61 is provided with an extension 71 so located that when this arm is in its extreme uppermost position and the clutch member 36 is in engagement with the clutch gear 30 the arm 67 cannot then be lowered to shift the clutch member 40 into engagement with the clutch gear 34. The extension 71 thus constitutes a safeguard against the simultaneous engagement of the oppositely running clutch gears.

The shifting lever 37 is provided with a long arm 72 carrying a cam roll adapted to be acted upon by the cams 51 and 54 which are associated with the worm wheel 49. As shown in Fig. 2 of the drawings, the shifter arm 37 has been swung by the solenoid 66 to engage the clutch member 39 with the clutch gear 32 so that the shaft 26 is being rotated at a high speed in a direction to move the grinding wheel slide at high speed toward the work. This action continues until the worm wheel 49 is rotated far enough to bring the cam face 52 into contact with the cam roller of the arm 72. When this occurs, the arm 72 is rocked positively downward in opposition to the pull of the solenoid 66, as will be presently explained, and the clutch member 36 is disengaged from the clutch gear 32. The same rotation of the worm wheel 49 has caused the segment 58 to close a circuit through the brushes 59 and 60, thereby energizing the solenoid 70 and swinging the shifting lever 42 to engage the clutch gear 34, which will continue rotation of the shaft 26 but at a slower speed to cause the slow feed of the grinding wheel into the work.

The construction of the caliper mechanism by which the solenoids are controlled will now be explained. Ways 130 are provided on the machine frame for supporting the caliper mechanism, which is mounted upon a bracket 132 shaped to fit the ways and to be clamped in any desired position thereon by a clamping plate 134 which is bolted to the lower side of the bracket. The bracket 132 has a plane upper face and has a carrier member 136 pivotally mounted in its lower flange upon a pin 138. Pivotally mounted by a pin 300 in the upper end of the carrier member is a frame piece 140 which carries two forwardly extending bars 142 and 144. The bar 144, as shown in Figs. 1 and 3, is provided with a boss in which is mounted a spring plunger 146 which bears upon the upper surface of the bracket 132 and urges the bars 142 and 144 and the parts carried thereby upwardly to a position determined by the engagement of the lower caliper member with the bottom of the work. The plunger 146 is provided at its upper end with a stop nut which serves to limit the downward movement of the plunger and, consequently, the upward

movement of the bar 144 when no work is engaged by the caliper members. The bars 142 and 144 are held together by rivets 148 which extend through the upper end of a curved bracket member 150. A horizontally disposed stop screw 152 projects through the bracket member 150. The stop screw 152 is adjustable and arranged to be locked in adjusted position by a transverse clamping screw 154. The stop screw 152 is intended to engage the work piece at a point substantially opposite the grinding point and to locate transversely the caliper mechanism. The bracket member 150 also carries in its lower end a vertically disposed contact screw 156 having a clamping screw 158, which contact screw 156 is designed to engage the bottom of the work piece, being pressed against it by the action of the spring 20 plunger 146 above referred to.

Between the bars 142 and 144 and above the bracket member 150 is pivotally mounted a rocker bar 160 upon a transverse pin 162. At its forward end the rocker bar carries a contact screw 164 having a clamping screw 166 and being adapted to engage the upper side of the work piece. The pin 162 is provided with removable flanged bushings 168 (Fig. 6) which are threaded into the bars 142 and 144. It is reduced at its outer ends and surrounded by a sleeve 170 in its enlarged intermediate portion. The sleeve 170 has an opening through which passes the lower end of a locking pin 172, threaded into the rocker bar 160 and adapted to engage a flat formed in the pin 162 beneath the opening in the sleeve 170 and serving to retain the pin against endwise displacement.

Journaled on the sleeve 170 which surrounds the pin 162, within the rocker bar 160, is a forked beam 180, the two branches of which are shown in section in Fig. 6. In the rear end of the rocker bar 160 is provided an adjusting screw 184, provided with a locking screw 185 and adapted to bear at its lower end upon a transverse web 182 in the forked beam 180. The adjusting screw 184 is provided with a graduated knurled head with which cooperates a spring 50 detent 186. The rocker bar 160 and the forked beam 180 constitute in effect a single two-part rocker, the arms of which may be relatively adjusted by turning the adjusting screw 184. A hairpin spring 188, located 55 between the forks of the beam 180, serves to maintain the end of the adjusting screw 184 always in engagement with the web 182. A leaf spring 189, mounted between the bars 142 and 144 and bearing upon the lower side 60 of the web 182 of the compound beam, serves to counterbalance the rear end thereof and maintain the contact screw 164 in engagement with the upper surface of the work piece. By turning the adjusting screw 184 65 downwardly, the forward end of the rocker

bar 160 is lowered and the contact screw 164 brought closer to the contact screw 156, thus affording convenient means for making a final adjustment for determining the point at which the caliper acts in controlling the 70 grinding. This construction of the caliper device, therefore, provides a two-part lever which carries one of the caliper points, and by adjusting the relation of the two parts of the lever the effective opening of 75 the caliper may be adjusted without displacing either the latch mechanism or the tripping device.

The electric switches, which are controlled by the beam 180 as its outer end moves upwardly, will now be described. The rear end of the beam 180, which is perforated for the sake of lightness and extends into the switch casing 191, is provided with a transverse extension 192 at either side, carrying an adjustable contact screw 194 at either end each arranged to engage and lift a tripping pawl 196 pivotally mounted in the switch casing and each cooperating at its free end with a single tooth ratchet disk 198 fast on a transverse shaft 200 journaled in a frame 202 and carrying a pinion 204 at its outer end. Each pinion 204 meshes with a gear 206 on a shaft journaled at the rear of the shaft 200 and having an elongated pinion 208. Each pinion 208 meshes with a vertically disposed rack 210 formed in a vertical rod 212, each of which extends upwardly through the cover 190 of the switch casing 191 where it is provided with 100 a knob by which it may be moved manually in one direction, that is to say, downwardly.

At its lower end each rod 212 is provided with a head 214. A sleeve 216 is mounted in line with and below each rod 212 in vertical bearings 222 on an insulated base 224. Each sleeve has a plug of insulating material secured in its upper end which is adapted to make an insulated contact with the head 214 of the rod 212. At its lower end each sleeve carries a carbon contact member 220. A compression spring 226, surrounding the sleeve 216 between the bearing member 222 and a ring 218 on the sleeve, serves normally to elevate each rod 212 and maintain the lower flange of the sleeve in contact with the lower end of the bearing member 222.

Mounted upon the base 224 in line with and below each of the bearing members 222 is a second bearing member 230, in which is mounted a similar sleeve 232 carrying a contact piece 234 and being maintained normally in its uppermost position with its lower flange against the bottom surface of 125 the bearing member 230. A lead wire 240 is connected to each of the contact members 220 which are controlled by the rods 212, and lead wires 242 are connected to each of the yieldingly mounted contact members 120

234. The contact members 234 are yieldingly mounted so as to permit over-travel of the cooperating contact members 220 and the establishment of good electrical contact 5 when the contact members 220 are moved downwardly.

When the operator depresses the knobs, forcing down the rods 212 to close the switch contacts, he compresses and energizes the 10 springs 226 and also rotates the ratchet disk 198 through its connected gear train. The ratchet disk is latched by its pawl 196 and being at a point in the train remote from the rack 210 the locking pressure is extremely light.

It will be understood that the caliper mechanism has a double pivot mounting which permits it to move freely up and down and toward and from the work, the pivots 20 being the pin 138 which connects the carrier member 136 with the bracket 132 and the pin 300 which connects the frame piece 140 with the carrier member. A lever 250 is provided for convenience in manually shifting 25 the caliper mechanism into and out of operative position. The pin 300 is extended out through the casing 191 and forms a fulcrum for the lever 250. A link 301 is pivotally connected at one end to the lever 250 by a bolt 302. The opposite end of the link 301 is slotted and adapted to engage the reduced outer end of a stud 303 set rigidly in the bracket 132. A spring 304 is attached at one end to the stud 303 and at 30 the opposite end to a stud 305 projecting from the link 301 and this tends normally to maintain the stud 303 in contact with the inner end of the slot in the link 301. The lever 250 is provided with a stop projection or lug 306 adapted to contact with the under side of the link 301 when in the 40 position shown in Fig. 1. In this position, the portion of the lever 250 between its fulcrum on the pin 300 and the bolt 302, together with the link 301, constitute a toggle mechanism which in the position shown is locked, that is, the pivot 300 lies above the line connecting the stud 303 with the bolt 302.

50 When the lever 250 is moved upwardly about its fulcrum pin (clockwise in Fig. 1) the toggle is broken and the entire caliper mechanism is moved to the front, as viewed in Fig. 1, and to an inoperative position away from the work. When the lever 250 is swung counterclockwise in the other direction, the caliper mechanism is moved into operative engagement with the work as determined by the three contact 55 screws, further motion of the toggle being prevented by engagement of the lug 306 on the lever 250 with the under side of the link 301.

The operation of the mechanism above 60 discussed is as follows. Appropriate pre-

liminary settings are first made in respect to the position of the worm wheel 13 with respect to the feed shaft 10 to bring the grinding wheel into the desired initial relation to the work piece 108. The caliper mechanism is moved into operative position opposite the grinding wheel 100 and a preliminary setting is made with the aid of a sample piece of finished work by turning the three contact screws to bring the screws 156 and 164 into engagement with that sample at diametrically opposite points and the rocker bar 180 is adjusted by the micrometer screw 184 into a position to just release the disk 198 from the pawl 196. Having 70 made that setting, the sample work piece is removed and a piece to be ground substituted therefor. This piece, being larger, will permit the disk 198 to be locked by the pawl 196 with the switch contacts 220 and 234 closed. The rods 212 are then depressed by the operator, where they will be held by the pawls 196 closing both the switches and energizing the solenoid 66 so that the shifting arm 37 is moved toward the right and the clutch member 39 engaged with the high speed in-feeding clutch gear 32. The circuit, through the other pair of contact members 220 and 234 and the solenoid 70, is not 75 closed because this includes the contact segment 58 and the brushes 59 and 60, so that this particular circuit is still open although both switches are closed in the switch box and both ratchet disks 198 are latched in position by their respective pawls 196.

The high speed in-feeding movement of the grinding wheel under the actuation of the clutch gear 32 is a movement preliminary to the actual grinding and brings the grinding wheel in from the inoperative initial position which it occupies during the insertion of the work to a position in which it is barely in grinding contact with the work. While it is making this movement, the worm wheel 49 has rotated in the direction shown by the arrow and to the position shown in Fig. 2, where the cam face 52 comes into contact with the roll and forces the lever 72 downwardly, moving the shifting arm 37 and the clutch members 36 toward the left, overcoming the pull of the solenoid 66 and disengaging the clutch member 36 from the clutch gear 32, thereby stopping the rapid movement of the grinding wheel toward the work. Just prior to the stopping of the rapid movement of the wheel toward the work the contact segment 58 closes the circuit through the brushes 59 and 60 so that the solenoid 70 is energized and the shifting arm 42 swung toward the left, engaging the clutch member 40 with the slow speed in-feeding clutch gear 34. Because of the pawl 46 serving as a driving connection between the clutch member 40 and the shaft 26, the engagement of the 80 85 90 95 100 105 110 115 120 125 130

clutch member 40 with gear 34 is ineffective until the higher speed clutch member 32 is fully disengaged. The grinding operation is, accordingly, commenced at a slow rate and under precise control. This continues until the caliper members approach each other sufficiently to trip first the pawl 196 of the left-hand switch assembly, as seen in Fig. 8, and then in its continued movement 5 the right-hand pawl 196. When the first pawl is tripped, the in-feeding movement of the grinding wheel is stopped as the spring 226 acts at once to elevate the left-hand rod 212 from the position shown in Fig. 5, wherein the circuit is represented as closed, to the position represented in Fig. 8, wherein the circuit is represented as broken. When the circuit in the solenoid 70 is broken 10 in this manner the spring surrounding the rod 68 acts to rock the bell crank lever 67 in a clockwise direction, disengaging the clutch member 40 from the low speed in-feeding clutch gear 34 and terminating the feeding movement of the grinding wheel. 15 The solenoid 66 is still energized, although its action is defeated by the concentric portion of the cam 51 which holds the arm 72 against movement in a clockwise direction. 20 When, however, the further grinding action which takes place after the in-feed is stopped in the manner described has reduced the work a slight further amount, the right-hand switch assembly is tripped in the same manner as above described and the circuit 25 of the solenoid 66 is opened and the spring 63 shifts the lever 72 and arm 37 together with the clutch 36 into engagement with the high speed out-feeding clutch gear 30, which then rapidly returns the entire mechanism 30 to the original inoperative position. This return motion is terminated by the cam 54 engaging the cam roll on the arm 72 and moving it upward against the tension of the spring 63 to the point where the clutch 35 member 36 is disengaged from the clutch gear 30. The arm 72 will be held in this position until the in-feeding for the next piece of work causes the worm wheel 49 to turn back and release the bell crank lever 37 to the action of the spring 63 or the pull of the solenoid 66. The operator may now 40 throw the lever 250 upward and backward, which withdraws the entire caliper mechanism from the work. He may then insert a new piece of work and repeat the operations just described. 45

It should be noted that the approaching movement of the grinding wheel is caused 50 by the closing of the electric circuit, which is done by the hand of the operator. The stopping of the grinding feed and the separating of the wheel and the work, on the other hand, are accomplished by the breaking of the circuits and this is effected auto- 55

matically by the action of the caliper mechanism.

Many pieces of work, however, when inserted in the grinding machine have a surface that is too rough and irregular to be at 70 once engaged by the caliper points without risk of injury. In such cases, after placing the work in the machine, the operator may press down plungers 212, though not latching them, thereby closing the electric contacts but not yet moving the caliper into operative engagement with the work. This closing of the circuit will start the rapid approaching movement which will, at the proper time, automatically shift, as above 75 described, to the slow grinding feed and when the wheel has ground away the rough outer surface of the work, the operator may then swing the caliper forward into operative engagement with the work and remove 80 his hand from the plungers 212 which will 85 then be held by the latches 196.

It should be noted that as the grinding wheel is a wearable element, the position of the entire feeding mechanism will gradually 90 change in relation to the point at which the work is ground to correct size. This relationship may be restored by means of the pinion 24 on the plunger 21 and its associated parts, rotating same through a distance as desired and relocking in another one of the series of holes 20. If the operator does not do this before an excessive amount of change of finishing position of the various parts has taken place, the increased 95 movement of the worm wheel 49 in the direction of the arrow in Fig. 2 will have brought the contacting segment 58 on insulating ring 57 to the point where it is out of contact with the brush 59, thereby opening the circuit of the solenoid 70 and stopping the slow feed. The mechanism will now be 100 inoperative, that is, it will not return automatically to its initial position. It would be necessary for the caliper to be withdrawn from the work, which would release the pawls 196 to open the contacts of the switches controlling both solenoids when the parts would return to their initial position. This last action described, namely the opening 105 the circuit of solenoid 70 by means of the withdrawal of the contacting segment 58 from contact with the brush 59, is a safety action to prevent the normal and intended cycle of movement of the various parts from being exceeded. 110

Having thus described my invention, what I claim as new and desire to secure by Letters Patent is:

1. An electrically controlled feeding mechanism for grinding machines comprising 115 a caliper device, a switch associated with said device and biased to an open position, a gear train connected with said switch, a latch which is arranged to hold said gear 120

train so that the switch remains closed, and a trip device restraining operation of the gear train which is arranged to be released by said caliper device.

5 2. An electrically controlled wheel feeding mechanism for grinding machines comprising a caliper device, a switch biased to an open position, a gear train to operate said switch, and a trip acting on the gear train which is arranged to be released by said caliper device.

10 3. An electrically controlled wheel feeding mechanism for grinding machines comprising a caliper device, a switch including a movable contact member, a spring to bias said contact member in an open position, a gear train connected thereto, a ratchet wheel in said gear train, a pawl arranged to engage said ratchet wheel to latch the contact member in a closed position, and means actuated by said caliper device to trip said pawl.

15 4. In a grinding machine, a work support and a grinding element relatively movable, feeding mechanism including a clutch arranged to move the two toward each other rapidly and preliminarily for a predetermined interval, a second clutch arranged to continue such approaching movement at slow speed, and a caliper device acting to release said second clutch to terminate said movement when the work has been reduced to a predetermined size.

20 5. In a grinding machine, a work support and a grinding element relatively movable, and feeding mechanism including a high speed in-feeding clutch, a low speed in-feeding clutch, a high speed out-feeding clutch, and means for automatically throwing said clutches successively into and out of action.

25 6. In a grinding machine, a work support and grinding element relatively movable, a caliper device, and feeding mechanism including a high speed in-feeding clutch, a low speed in-feeding clutch governed in its action by said caliper device, a high speed out-feeding clutch, and means for automatically terminating its action.

30 7. In a grinding machine, a work support and grinding element relatively movable, a caliper device, and feeding mechanism including a high speed in-feeding clutch, mechanical timing means therefor, a low speed in-feeding clutch arranged to be thrown automatically into action and to be thrown out of action by said caliper device, and a high speed out-feeding clutch arranged to be thrown into action by the operation of said caliper device.

35 8. In a grinding machine, a work support and grinding element relatively movable, a caliper device, and feeding mechanism including a high speed in-feeding clutch, a low speed in-feeding clutch, automatic tim-

ing mechanism for terminating the action of the high speed clutch and initiating the action of the low speed clutch, and caliper-controlled means for terminating the action of the low speed clutch.

70 9. In a grinding machine, a work support and grinding element relatively movable, a caliper device, and feeding mechanism including a high speed in-feeding clutch, a low speed in-feeding clutch, automatic timing mechanism for determining the sequence of operation of said high speed and low speed clutches, caliper controlled means for terminating the action of the low speed clutch, and an out-feeding clutch controlled in its action by said caliper device.

75 10. In a grinding machine, a work support and grinding element relatively movable, a caliper device, and feeding mechanism including a high speed in-feeding clutch, a low speed in-feeding clutch and an out-feeding clutch arranged for consecutive operation, together with caliper-controlled means for governing the operation of said two latter clutches, and means for positively preventing simultaneous engagement thereof.

80 11. In a grinding machine, a work support and grinding element relatively movable, feeding mechanism including a single driving shaft having a high speed in-feeding clutch, a low speed in-feeding clutch and an out-feeding clutch mounted thereon, driving connections to each clutch, automatic means for timing the action of said clutches, and means to permit over-running of the low speed in-feeding clutch when the high speed in-feeding clutch is in operation.

85 12. In a grinding machine, a work support and grinding element relatively movable, feeding mechanism including a single driving shaft having a high speed in-feeding clutch, a low speed in-feeding clutch and an out-feeding clutch mounted thereon, driving connections to each clutch, a timing shaft driven by said driving shaft, and clutch timing mechanism actuated thereby.

90 13. In a grinding machine, a work support and grinding element relatively movable, a caliper device, in-feeding and out-feeding clutches having a common driven member arranged to engage first with the in-feeding clutch, cam controlled means for disengaging said driven clutch member from the in-feeding clutch, and caliper-controlled means for engaging said member with said out-feeding clutch.

95 14. In a grinding machine, a work support and grinding element relatively movable, a caliper device, in-feeding and out-feeding clutches having a common driven member arranged to engage first with the in-feeding clutch, cam controlled means for disengaging said driven clutch member from the in-feeding clutch, a second in-

- feeding clutch arranged to be automatically thrown into action when said first mentioned in-feeding clutch is disengaged, and caliper-controlled means for disengaging said latter in-feeding clutch and engaging said out-feeding clutch. 5 70
15. In a grinding machine, a feed controlling caliper device comprising cooperating contact members, a two-part lever for carrying one of said members, a trip mounted in said lever, and means for adjusting the parts of said lever to vary the effective opening of the caliper without substantially displacing the trip. 10 75
- 15 16. In a grinding machine, a feed controlling caliper device comprising oppositely disposed members each having a contact point on the work, latch mechanism carried by one of said members, a tripping device carried by the other member, and means for adjusting the effective opening of the caliper without substantially displacing either the latch mechanism or the tripping device. 20 80
17. In a grinding machine, automatic feeding mechanism, an actuating system for controlling said feeding mechanism, a caliper device, a pair of spring operated controlling members located side by side and arranged to be latched under tension 25 85
- 30 by the operator, a gear train associated with each controlling member and having a latch remote from its controlling member, and means operated by the caliper device for tripping one latch after another to render 35 90
- 35 the controlling members successively effective in varying the action of the feeding mechanism. 95
18. In a grinding machine, a work support and a grinding element mounted for relative movement, multi-speed feeding mechanism to effect a continuous relative movement therebetween, means actuated by and in timed relation to the feeding mechanism to change the speed of the feeding 40 100
- 45 mechanism, and means including a caliper device engageable with the work which acts to stop said feeding movement when the work has been reduced to a predetermined size. 105
- 50 19. In a grinding machine, a work support and a grinding element mounted for relative movement, multi-speed feeding mechanism including a rotatable feed screw and nut to effect a continuous relative movement therebetween, means actuated by and in timed relation to the rotation of the feed screw to change the speed of the feeding mechanism, and means including a caliper device engageable with the work which 55 110
- 60 acts to stop said feeding movement when the work has been reduced to a predetermined size. 115
20. In a grinding machine, a work support and a grinding element mounted for relative movement, multi-speed feeding 65 120
- 125
- mechanism for effecting a continuous relative movement therebetween, means operated by movement of the feeding mechanism to reduce the speed of the relative movement, and means including a caliper device constructed and arranged to interrupt said relative movement when the work has been reduced to a predetermined size. 70
21. In a grinding machine, a support for a piece of work, a feed control caliper device, a bracket for supporting said caliper device, and a carrier member pivotally mounted on said bracket, said caliper device comprising oppositely disposed members each having a contact point on the work, one of said members being pivotally mounted on said carrier and slidable on said bracket toward and away from the work by reason of the pivotal mounting of the carrier member. 75
22. In a grinding machine, a feed controlling caliper device comprising oppositely disposed members each having a contact point on the work, a bracket, means for slidably supporting said caliper device for movement toward and away from the work, a lever interposed between said bracket and said caliper device for sliding the latter, and means associated with said lever constructed and arranged to form a toggle mechanism to hold the caliper mechanism in operative engagement with the work. 80
23. A grinding machine comprising a work support, a wheel slide, a grinding wheel rotatably mounted thereon, a feeding device to move the wheel towards and from the work, a sizing mechanism having a caliper engaging the work and an electrically controlled multi-speed power mechanism to operate said feeding device, including a switch having two sets of contact members arranged to be initially latched in a closed position by the operator and thereby cause said mechanism to start the rapid approaching movement of the grinding wheel, one set of contact members being tripped by said caliper device when the wheel approaches the surface of the work to produce a slow but uniform grinding feed of the wheel, and the other set being arranged to be tripped when the work has been ground to a predetermined size to cause an outward feeding movement of the grinding wheel. 95
24. A grinding machine comprising a work support, a wheel slide, a grinding wheel rotatably mounted thereon, a feeding device to move the grinding wheel towards and from the work, a sizing mechanism having a caliper engaging the work and a power operated mechanism including a clutch to continuously drive said feeding device and an electrically operated mechanism including a switch arranged to be initially latched in a closed position by the operator to con- 100

- 125

nect the clutch and thereby start an infeed of the wheel and to be tripped by said caliper device to disconnect said clutch when the work has been ground to a predetermined size to stop the infeed of the wheel.

25. A grinding machine comprising a work support, a wheel slide, a grinding wheel rotatably mounted thereon, a feeding device to move the wheel towards and from the work, a sizing mechanism having a caliper to engage the work, and a power operated mechanism including a clutch to continuously drive said feeding device and an electrically operated mechanism including a spring actuated switch which is arranged to be latched in a closed position by the operator to connect the clutch and thereby cause said mechanism to start the infeed of the wheel and to be tripped by the caliper device when the work has been ground to a predetermined size to stop the infeed of the wheel.

26. In a grinding machine, a work support and a rotatable grinding wheel, a feeding mechanism to feed the grinding wheel towards and from the work, a power operated gear driving mechanism to automatically actuate said feeding mechanism continuously, including high speed gearing to rapidly position the grinding wheel adjacent to the work, a slow speed gearing for feeding the grinding wheel to rough grind the work, a high speed reverse gearing to rapidly move the grinding wheel away from the work, means actuated automatically in timed relation with the wheel movement to change the gear driving mechanism from high speed to low speed, and a caliper device engaging the work and arranged to control the power operated gear mechanism to stop the slow grinding feed and to reverse the feed so as to accurately size the work.

27. In a grinding machine, a work support and a rotatable grinding wheel, a reversing feeding mechanism to feed the grinding wheel toward and from the work, a power drive mechanism to actuate said mechanism to automatically feed the grinding wheel continuously toward or from the work, first at a rapid rate to position the grinding wheel adjacent to the work, then at a slower rate to rough grind the work, then a dwell to finish grind the work and a clutch for reversing the feeding mechanism to produce a rapid and positive rearward movement of the wheel, and a caliper device engaging the work and arranged to control said power drive mechanism so as to accurately size the work.

28. A grinding machine comprising a work support and a rotatable grinding wheel which are movable relatively toward and from each other, a caliper device, a feeding mechanism arranged to relatively move said support and wheel, and a multi-

speed power mechanism for actuating said feeding mechanism to automatically and continuously feed the grinding wheel, first at a high speed and then at a slow speed, said low speed infeed movement being governed in its action by said caliper device, a high speed mechanism to positively actuate the feed mechanism to feed the wheel rearwardly, and means for automatically terminating its action.

29. A grinding machine comprising a work support, a grinding element movable toward and from said support, a caliper device, a feeding mechanism arranged to feed said support relatively to each other and a multi-speed power driving mechanism to actuate said feeding mechanism including a high speed infeeding mechanism, mechanically actuated mechanism for controlling said means, a low speed infeeding means arranged to be thrown automatically into action and to be thrown out of action by said caliper device, and a high speed outfeeding means arranged to be thrown into action by the operation of said caliper device.

30. A feeding mechanism for grinding machines comprising a work support and a rotatable grinding wheel which are movable relatively towards and from each other, a caliper device, a feeding mechanism, and a multi-speed power driving mechanism including a high speed gearing to actuate the feeding mechanism to feed the wheel rapidly toward the work, a low speed mechanism to feed the wheel at a slower or grinding speed, automatic timing mechanism actuated by the feeding mechanism for terminating the action of the high speed mechanism and initiating the action of the low speed mechanism, and a caliper controlled means for stopping the low speed mechanism.

31. A grinding machine comprising a work support, a wheel slide, a grinding wheel rotatably mounted thereon, a feeding mechanism to move the wheel towards and from the work, a multi-speed reversible power mechanism to operate said feed device at a high and a low speed towards the work and at a given speed away from the work, means actuated when the wheel has reached a predetermined position relative to the work to change the wheel feed from a high to a low speed, an electrically controlled device, including a caliper device, engaging the work and a switch having two sets of contact members, one set being actuated in response to movement of the device to a position indicating that the work has been reduced to a predetermined size, to disconnect the power mechanism and stop the grinding feed of the wheel, and the other set being arranged to be actuated when the work has been ground to a further predetermined size.

terminated size to actuate reversible mechanism and cause a positive outward feeding movement of the grinding wheel.

32. A grinding machine having a work support, a grinding wheel movable towards and from the work, a reversible multi-speed feed mechanism for moving the wheel toward the work at a high and a low speed and for moving the wheel away from the work, a reversing mechanism including a control device for stopping, changing the speed of and reversing said feed mechanism, means acting to operate the control device and change the wheel feed from a high to a low speed when it reaches a given position relative to the work, a caliper device having a movable feeler which measures a reduction in the size of the work being ground, electrically operated means responsive to one position of said feeler while measuring the work during the grinding operation which is connected to actuate said control device and stop the infeed of the grinding wheel when the work has reached a first predetermined size and cause the wheel to grind the work during a dwell period, and electrically operated means responsive to a second position of the feeler when the work has been reduced to a further predetermined size which causes the control device to reverse the wheel feed and cause the grinding wheel to withdraw from grinding contact with the work.
